(57) **ABSTRACT**

Systems and methods for removing microfeature workpiece surface defects are disclosed. A method for processing a microfeature workpiece in accordance with one embodiment includes removing surface defects from a surface of a microfeature workpiece by engaging the surface with a buffering medium having a first hardness, and moving at least one of the workpiece and the buffering medium relative to the other. After removing the surface defects and before adding additional material to the microfeature workpiece the method can further include engaging the microfeature workpiece with a polishing pad having a second hardness greater than the first hardness. Additional material can be removed from the microfeature workpiece by moving at least one of the microfeature workpiece and the polishing pad relative to the other.

**SYSTEMS AND METHODS FOR REMOVING
MICROFEATURE WORKPIECE SURFACE
DEFECTS**

**CROSS-REFERENCE TO RELATED
APPLICATION**

This application is a divisional of U.S. patent application Ser. No. 11/181,341, filed Jul. 13, 2005, which is incorporated herein by reference in its entirety.

TECHNICAL FIELD

The present invention is directed generally to systems and methods for removing microfeature workpiece surface defects, for example, prior to planarizing such workpieces.

BACKGROUND

Mechanical and chemical-mechanical planarization and polishing processes (collectively "CMP") remove material from the surfaces of microfeature workpieces in the production of microelectronic devices and other products. FIG. 1 schematically illustrates a system that includes a rotary CMP machine 10 and a buffering machine 20. The CMP machine 10 has a platen 16, a polishing pad 31 on the platen 16, and a carrier 11 adjacent to the polishing pad 31. A platen drive assembly 17 rotates the platen 16 and polishing pad 31 (as indicated by arrow A) and/or reciprocates the platen 16 and polishing pad 31 back and forth (as indicated by arrow B) during planarization. The carrier 11 has a carrier head 19 to which a microfeature workpiece 50 may be attached. The carrier head 19 may be a weighted, free-floating wafer carrier, or a carrier actuator assembly 12 may be attached to the carrier head 19 to impart rotational motion to the microfeature workpiece 50 (as indicated by arrow C) and/or reciprocate the workpiece 50 back and forth (as indicated by arrow D).

The polishing pad 31 and a polishing solution 32 define a polishing medium 30 that mechanically and/or chemically mechanically removes material from the surface of the microfeature workpiece 50. The polishing solution 32 may be a conventional CMP slurry with abrasive particles and chemicals that etch and/or oxidize the surface of the microfeature workpiece 50, or the polishing solution 12 may be a "clean" nonabrasive planarizing solution without abrasive particles. In most CMP applications, abrasive slurries with abrasive particles are used on nonabrasive polishing pads, and clean nonabrasive solutions without abrasive particles are used on fixed-abrasive polishing pads.

To planarize the microfeature workpiece 50 with the CMP machine 10, the carrier head 19 presses the workpiece 50 face-down against the polishing pad 31. More specifically, the carrier head 19 generally presses the microfeature workpiece 50 against the polishing solution 32 on a polishing surface 33 of the polishing pad 31, and the platen 16 and/or the carrier head 19 move to rub the workpiece 50 against the polishing surface 33. As the microfeature workpiece 50 rubs against the polishing surface 33, the polishing medium 30 removes material from the face of the workpiece 50.

After the microfeature workpiece 50 has been polished, it is moved to the buffering machine 20. The buffering machine 20 includes many features generally similar to those of the CMP machine 10, but instead of the polishing medium 30, the buffering machine 20 includes a buffering medium 40. The buffering medium 40 in turn includes a buffering pad 41 having a buffering surface 43 that supports a buffering solution 42. The

2

buffering solution 42 can be the same as or different than the polishing solution 32. The buffering surface 43 is generally softer than the polishing surface 33 so as to gently remove residual contaminants from the workpiece 50 after the preceding CMP operation.

While the foregoing technique has proved useful for removing at least some surface defects from the microfeature workpiece 50 after a CMP operation, such defects still may form, and such defects may not always be removed via the buffering technique. Accordingly, it may be desirable to further improve the uniformity of workpieces that are processed using CMP techniques.

BRIEF DESCRIPTION OF THE DRAWINGS

FIG. 1 is a partially schematic illustration of a CMP machine and a buffering machine configured in accordance with the prior art.

FIG. 2A is a partially schematic illustration of a portion of a microfeature workpiece having surface defects prior to undergoing a CMP operation.

FIG. 2B is a flow diagram illustrating a method for removing surface defects from a microfeature workpiece prior to CMP processing.

FIG. 3 is a partially schematic illustration of system components that may be used to remove material from a microfeature workpiece prior to a CMP operation.

FIG. 4 is a partially schematic, plan view of a tool configured to planarize microfeature workpieces and remove surface defects from such workpieces before and after planarization.

DETAILED DESCRIPTION

The present invention is directed generally toward systems and methods for removing microfeature workpiece surface defects. One of the drawbacks associated with the arrangement described above with reference to FIG. 1 is that the microfeature workpiece may arrive at the CMP machine with contaminant materials already carried by and/or embedded in the surfaces of the workpiece. It is believed that such contaminants may contribute to the formation of additional surface defects during the ensuing CMP operation, and that not all such surface defects may be effectively removed by a post-CMP buffering process. As a result, the existing methods and tools may not produce microfeature workpieces having the desired level of planarity and uniformity.

One aspect of the invention is directed toward a method for processing a microfeature workpiece, and includes removing surface defects from a surface of the microfeature workpiece by engaging the surface with a buffering medium having a first hardness, and moving at least one of the workpiece and the buffering medium relative to the other. The method can further include engaging the microfeature workpiece with a buffering pad having a second hardness greater than the first hardness, after removing the surface defects, and before adding additional material to the microfeature workpiece. Material can then be removed from the microfeature workpiece by moving at least one of the microfeature workpiece and the buffering pad relative to the other.

In particular embodiments, the buffering medium can have a Shore D hardness of about zero, while the buffering pad can have a Shore D hardness of about 20 or higher (e.g., from about 50 to about 60). Removing the surface defects can include removing a layer having a thickness of less than 10 microns from the microfeature workpiece. In still further

particular embodiments, removing surface defects can include removing particulate contaminants, surface scratches, or both.

An apparatus in accordance with another aspect of the invention includes a first station having a buffering medium with a first hardness, a second station having a polishing pad with a second hardness greater than the first, and an automated transfer device positioned to move a microfeature workpiece between the first and second stations. The apparatus can further include a controller operatively coupled to the automated transfer device. The controller can contain instructions for directing the automated transfer device to place a microfeature workpiece at the first station before placing the same microfeature workpiece at the second station.

In yet another aspect, an apparatus for processing microfeature workpieces can include a first station having a buffering medium with a first hardness, a second station having a polishing pad with a second hardness greater than the first, and a third station having a buffering medium with a third hardness less than the second. The apparatus can further include an automated transfer device positioned to move a microfeature workpiece among the first, second and third stations. In particular aspects, the apparatus can further comprise a controller operatively coupled to the automated transfer device, with the controller containing instructions for directing the automated transfer device to place a microfeature workpiece at the first station before placing the same microfeature workpiece at the second station. The controller can further include instructions for directing the automated transfer device to place the microfeature workpiece at the third station after placing the same microfeature workpiece at the second station.

As used herein, the terms "microfeature workpiece" and "workpiece" refer to substrates in and/or on which microelectronic devices are integrally formed. Microfeature polishing pads typically include pads configured to remove material from microfeature workpieces during the formation of micro-devices. Typical micro-devices include microelectronic circuits or components, thin-film recording heads, data storage elements, microfluidic devices, and other products. Micro-machines and micromechanical devices are included within this definition because they are manufactured using much of the same technology that is used in the fabrication of integrated circuits. Substrates can be semiconductive pieces (e.g., doped silicon wafers or gallium arsenide wafers), non-conductive pieces (e.g., various ceramic substrates), or conductive pieces. In some cases, the workpieces are generally round, and in other cases, the workpieces have other shapes, including rectilinear shapes. Several embodiments of buffering media and associated systems and tools are described below. A person skilled in the relevant art will understand, however, that the invention may have additional embodiments, and that the invention may be practiced without several of the details of the embodiments described below with reference to FIGS. 2A-4.

FIG. 2A is a partially schematic illustration of a portion of a microfeature workpiece 250, illustrating surface defects 253 that may be present before the microfeature workpiece 250 undergoes a CMP process. The microfeature workpiece 250 can include two major surfaces 251 (shown as first and second major surfaces 251a, 251b) and an intermediate edge surface 252. Any of these surfaces can include one or more surface defects 253. For purposes of illustration, the surface defects 253 are shown schematically and are not shown to scale. The surface defects 253 can include surface contaminants 254, e.g., particulates that rest on and/or adhere to the surface, but are not embedded in the surface. The surface

defects 253 can also include partially embedded contaminants 255 that may be more firmly attached to the surface. The surface defects 253 can still further include surface scratches 256 that extend a short distance D from the corresponding surface. In one embodiment, the surface scratches 256 can extend for a distance D that is on the order of a few hundred angstroms or less (e.g., less than 10 microns).

It is believed that if at least some of the foregoing surface defects (e.g., the surface contaminants 254 and/or partially embedded contaminants 255) break away from the microfeature workpiece 250 during CMP processing, they may damage the microfeature workpiece 250, for example, by causing scratches. Accordingly, aspects of the invention are directed to methods for reducing or eliminating the likelihood for such damage to occur. FIG. 2B is a flow diagram illustrating a process 200 for handling a microelectronic workpiece prior to a CMP operation. The process 200 can include removing surface defects from a microfeature workpiece using a buffering medium having a first hardness (process portion 202). 10 After removing the surface defects, and before adding additional material to the workpiece, the method can further include removing material from the workpiece with a polishing pad having a second hardness greater than the first hardness (process portion 204). For example, process portion 204 15 can include polishing and/or planarizing the microfeature workpiece in a CMP process after buffering the workpiece, but before adding a new layer of material (e.g., a metal or dielectric material) to the workpiece. After the workpiece has been polished and/or planarized, the method can include a post-20 process (process portion 206). In one aspect of this embodiment, the post-CMP buff can be carried out by the same buffering medium as was used to carry out the initial buffering process (process portion 208). In another embodiment, a different buffering medium can be used for post-CMP buffering 25 30 (process portion 210). Further details of systems for carrying out the foregoing processes are described below with reference to FIGS. 3 and 4.

FIG. 3 is a partially schematic illustration of a first buffering machine 320a, a planarizing machine 310, and an optional second buffering machine 320b. The buffering machines 320a, 320b and the planarizing machine 310 can include several common features. Such features include a platen 316 coupled to a drive assembly 317 for rotational movement (indicated by arrow A) and/or a translational movement (indicated by arrow B). A carrier 311 can be positioned proximate to the platen 317 and can include a carrier head 319 coupled to an actuator assembly 312 for rotational motion (indicated by arrow C) and/or a translational motion (indicated by arrow D). The carrier head 319 can include a resilient pad 315 that is positioned to contact a microfeature workpiece 250 carried by the carrier 311 for movement relative to the platen 316.

The platens 316 of the buffering machines 320a, 320b can support buffering media 340 (shown as a first buffering machine 340a and a second buffering machine 340b), while the platen 55 316 of the planarizing machine 310 can support a polishing medium 330. For example, the first buffering machine 320a can include a first buffering medium 340a that in turn includes a first buffering pad 341a and a first buffering solution 342a. The first buffering pad 341a is carried on the platen 316 by an underpad 318 and has an outwardly facing buffering surface 343a that contacts the downwardly facing surface 251a of the microfeature workpiece 250.

The first buffering pad 341a can be softer than a typical CMP polishing pad. For example, the first buffering pad 341a can have a Shore D hardness of about zero in one embodiment. The first buffering pad 341a can include a generally spongy material and can have a configuration generally similar to that

of a Politex or UR2 pad available from Rohm & Haas Electronic Materials of Philadelphia, Pa. In at least some embodiments, the first buffering pad 341a can be compliant enough that, with a selected level of down force applied by the carrier head 319 to the microfeature workpiece 250, the first buffering pad 341a can remove material from the edge surfaces 252 of the microfeature workpiece 250. The action of the first buffering pad 341a can be assisted by the first buffering solution 342a. In one embodiment, the first buffering solution 342a can include a conventional CMP slurry, and in other embodiments, the first buffering solution 342a can have other compositions.

In any of the foregoing embodiments, the process of buffering the microfeature workpiece 250 at the first buffering machine 320a can remove some or all of the surface defects 253 described above with reference to FIG. 2A. After such defects have been removed, the microfeature workpiece 250 can be moved to the CMP machine 310 for planarizing and/or polishing. The CMP machine 310 can include components generally similar to those described above with reference to the first buffering machine 320a, except that the first buffering medium 340a can be replaced with a polishing medium 330. The polishing medium 330 can include a polishing pad 331 having a polishing surface 333 on which a polishing solution 332 is disposed. The polishing pad 331 can be harder than the first buffering pad 341a to remove more substantial quantities of material from the surface of the microfeature workpiece 250. For example, the polishing pad 331 can have a Shore D hardness of about 20 or higher in some embodiments, and a Shore D hardness of from about 50 to about 60 in further particular embodiments. Accordingly, while the first buffering medium 340a may tend to remove surface defects, including scratches to a depth of less than about 10 microns, the polishing medium 330 may be used to remove more significant amounts of material, including layers having thicknesses on the order of tens or hundreds of microns.

The process of polishing the microfeature workpiece 250 may also leave residual surface defects, which can be removed in a post-CMP buffering process. In one embodiment, the microfeature workpiece 250 can be returned to the first buffering machine 320a for removal of surface defects caused by the processes carried out at the CMP machine 310. In another embodiment, the microfeature workpiece 250 can be moved to the second buffering machine 320b for removal of such surface defects. The second buffering machine 320b can be generally similar to the first buffering machine 320a, and can include a second buffering medium 340b. The second buffering medium 340b can include a second buffering pad 341b having a second buffering surface 343b which carries a second buffering solution 342b. In some embodiments, the second buffering pad 341b and/or the second buffering solution 342b can be the same as the corresponding first buffering pad 341a and the first buffering solution 342a. In other embodiments, either or both of these components can be different. For example, if the nature of the surface defects to be removed after CMP processing is different than the nature of the surface defects to be removed prior to CMP processing, the second buffering medium 340b can be different than the first polishing medium 340a. In further particular instances, the hardness of the second buffering pad 341b can be different than the hardness of the first buffering pad 341a, and/or the chemical and/or abrasive characteristics of the second buffering solution 342b can be different than the corresponding characteristics of the first buffering solution 342a.

In some embodiments, the second buffering machine 320b if used, may be located at a tool that is different than a tool that carries the first buffering machine 320a and the CMP machine

310. In such an embodiment, the microfeature workpiece 250 can be transported in a suitable container to the second buffering machine 320b for a post-CMP buffering process. In other embodiments, the CMP machine 310 can also be located at a different tool than the first buffering machine 320a, in which case the microfeature workpiece 250 is transported from the first buffering machine 320a to the CMP machine 310, also in a suitable container. In still further embodiments, all three machines can be co-located in a single tool, as described below with reference to FIG. 4.

FIG. 4 is a partially schematic, top plan view of a tool 411 that includes a polishing station 402 and multiple buffering stations 401 (shown as a first buffering station 401a and a second buffering station 401b). The tool 411 can also include an I/O station 403 at which microfeature workpieces 250 enter and exit the tool 411. An automated transfer device 404 (e.g., a robot) can include an end effector 405 suitable for moving the workpieces 250 from the I/O station 403 among the various other stations of the tool for processing, and then back to the I/O station 403 after processing has been completed.

The first buffering station 401a can include the first buffering medium 340a, and the second buffering station 401b can include the second buffering medium 340b. The polishing station 402 can include the polishing medium 330. In operation, the automated transfer device 404 can move a microfeature workpiece 250 from the I/O station 403 to the first buffering station 401a where surface defects are removed prior to polishing/planarization. The automated transfer device 404 can then move the microfeature workpiece 250 to the polishing station 402 for polishing/planarization using a polishing pad 331 having a hardness greater than the first buffering pad 341a. As described above with reference to FIG. 2A, the microfeature workpiece 250 can be moved from the first buffering station 401a to the polishing station 402 without undergoing an intermediate material application process. However, the microfeature workpiece 250 may undergo other intermediate processes, for example, a rinsing process.

In one mode of operation, the microfeature workpiece 250 can then be moved to the second buffering station 401b for a post-CMP buffering process and then back to the input/output station 403 for removal from the tool 411. In another embodiment, for example, when the second buffering medium 340b is the same as the first buffering medium 340a, the microfeature workpiece 250 can be moved from the polishing station 402 to whichever buffering station 401a, 401b is available at that time.

Directions for the motion of the automated transfer device 404 can be provided by a controller 406 that is operatively coupled to the automated transfer device 404. The controller 406 can include a programmable computer, and the directions can include computer-executable instructions, including routines executed by the programmable computer. The term "computer" as generally used herein refers to any data processor and can include hand-held devices (including palm-top computers, wearable computers, cellular or mobile phones, multi-processor systems, processor-based or programmable consumer electronics, network computers, mini computers and the like). Directions and/or related aspects of the invention may be stored or distributed on computer-readable media, including magnetic or optically readable or removable computer disks, as well as distributed electronically over networks. The directions may be "hard-wired" functions carried out by the computer, and/or the directions or particular portions of the directions may be changeable, for example, by an end-user or by service personnel.

One feature of at least some of the foregoing embodiments is that they can include removing surface defects from a

surface of a microfeature workpiece via a buffing medium, before engaging the microfeature workpiece (or a surface thereof) with a polishing medium, and before applying additional material to the microfeature workpiece (or a surface thereof). For example, the removed surface defects can include constituents that would otherwise break away from the microfeature workpiece when contacted with the polishing pad. An expected benefit of this arrangement is that it will reduce or eliminate the number of surface defects in the microfeature workpiece prior to a CMP material removal process, and can therefore rehabilitate a workpiece having surface defects. It is believed that such surface defects may, when placed in contact with a relatively hard polishing pad, scratch or further scratch the surface of the microfeature workpiece and create additional surface defects. Accordingly, by removing surface defects prior to the polishing process, the likelihood for creating additional surface defects can be reduced or eliminated.

Another feature of at least some embodiments of the foregoing arrangement is that they can include a tool having both a pre-CMP buffing station and a post-CMP buffing station, for example, as shown in FIG. 4. This is unlike at least some conventional tools (e.g., the Mirra polishing tool, available from Applied Materials of Santa Clara, Calif.) which include a single buffing station and multiple CMP stations. An advantage of arrangements having features such as those described above with reference to FIG. 4 is that they can support continuous processing of microfeature workpieces in a manner that includes both buffing the workpiece before conducting a CMP process, and buffing the microfeature workpiece after conducting a CMP process. As described above, this arrangement can reduce and/or eliminate the likelihood for creating additional surface defects on the microfeature workpiece.

From the foregoing, it will be appreciated that specific embodiments of the invention have been described herein for purposes of illustration, but that various modifications may be made without deviating from the invention. For example, particular aspects of the invention have been described in the context of rotary buffing and CMP stations, while in other embodiments, the buffing and/or polishing media described above can be applied to linearly actuated (e.g., web format) machines that include buffing and/or polishing pads wound from a supply roller to the takeup roller. Aspects of the invention described in the context of particular embodiments may be combined or eliminated in other embodiments. For example, the second buffing machine 320b described above with reference to FIG. 3 may be eliminated in some embodiments. Further, while advantages associated with certain embodiments of the invention have been described in the context of those embodiments, other embodiments may also exhibit such advantages, and not all embodiments need necessarily exhibit such advantages to fall within the scope of the invention. Accordingly, the invention is not limited except as by the appended claims.

We claim:

1. An apparatus for processing microfeature workpieces, comprising:
  - a first station having a buffing medium with a first hardness;
  - a second station having a polishing pad with a second hardness greater than the first hardness;
  - an automated transfer device positioned to move a microfeature workpiece between the first and second stations, the microfeature workpiece having a first exposed surface and particulates resting on or at least partially embedded in the first exposed surface; and
  - a controller operatively coupled to the automated transfer device, the controller containing a computer-readable

medium having instructions that cause the controller to perform a method comprising—

directing the first exposed surface of the microfeature workpiece to contact the buffing medium at the first station to remove the particulates from the first exposed surface of the microfeature workpiece;

directing the automated transfer device to transfer the microfeature workpiece from the first station to the second station after the particulates are at least partially removed from the first exposed surface; and

thereafter, directing the first exposed surface of the microfeature workpiece to engage the polishing pad at the second station to remove material from the first exposed surface to create a second exposed surface different than the first exposed surface.

2. The apparatus of claim 1, further comprising an input/output station positioned to receive microfeature workpieces, and wherein the automated transfer device is positioned to move microfeature workpieces into and out of the input/output station.

3. The apparatus of claim 1 wherein the instructions are stored on a computer-readable medium.

4. The apparatus of claim 1, further comprising a third station having a buffer medium with a third hardness less than the second hardness, wherein the automated transfer device is positioned to move a microfeature workpiece among the first, second and third stations.

5. The apparatus of claim 1 wherein the buffing medium includes a buffing pad having a Shore D hardness of about zero.

6. The apparatus of claim 1 wherein the polishing pad has a Shore D hardness of about 20 or higher.

7. The method of claim 1 wherein the polishing pad has a Shore D hardness of from about 50 to about 60.

8. An apparatus for processing microfeature workpieces, comprising:

a first station having a first buffing medium with a first hardness;

a second station having a polishing pad with a second hardness greater than the first hardness;

a third station having a second buffing medium with a third hardness less than the second hardness;

an automated transfer device positioned to move a microfeature workpiece among the first, second and third stations, the microfeature workpiece having a first exposed surface and particulates resting on or at least partially embedded in the first exposed surface; and

a controller operatively coupled to the automated transfer device, the controller containing a computer-readable medium having instructions that cause the controller to perform a method comprising—

directing the first exposed surface of the microfeature workpiece to contact the first buffing medium at the first station to remove the particulates from the first exposed surface of the microfeature workpiece;

directing the automated transfer device to transfer the microfeature workpiece from the first station to the second station after the particulates are at least partially removed from the first exposed surface; and

thereafter, directing the first exposed surface of the microfeature workpiece to engage the polishing pad at the second station to remove material from the first exposed surface to create a second exposed surface different than the first exposed surface;

9

directing the automated transfer device to transfer the microfeature workpiece from the second station to the third station after the second exposed surface is created; and

directing the second exposed surface to contact the second buffering medium at the third station.

9. The apparatus of claim **8**, further comprising a controller operatively coupled to the automated transfer device, the controller containing instructions for directing the automated transfer device to place a microfeature workpiece at the first station before placing the same microfeature workpiece at the second station. 10

10. The apparatus of claim **9** wherein the controller contains instructions for directing the automated transfer device to place a microfeature workpiece at the third station after placing the same microfeature workpiece at the second station. 15

11. The apparatus of claim **8** wherein the first hardness is approximately the same as the third hardness. 20

12. The apparatus of claim **8** wherein the buffering medium at the first station includes a buffering pad having a Shore D hardness of about zero. 25

13. The apparatus of claim **8** wherein the buffering pad at the second station has a Shore D hardness of about 20 or higher. 25

14. The apparatus of claim **8** wherein the buffering pad at the second station has a Shore D hardness of from about 50 to about 60. 30

15. The apparatus of claim **8** wherein a composition of the buffering medium at the third station is at least approximately the same as a composition of the buffering medium at the first station. 35

16. An apparatus for processing microfeature workpieces, comprising:

a first station having a buffering medium with a first hardness;

10

a second station having a buffering pad with a second hardness greater than the first hardness;

an automated transfer device positioned to move a microfeature workpiece between the first and second stations, the microfeature workpiece having a first exposed surface, a second exposed surface, and a side surface between the first and second exposed surfaces; and a controller operatively coupled to the automated transfer device, the controller containing a computer-readable medium containing instructions that cause the controller to perform a method comprising—

directing the first exposed surface and at least a portion of the side surface of the microfeature workpiece to engage the buffering medium at the first station to remove surface defects from the first exposed surface and the side surface;

directing the automated transfer device to transfer the microfeature workpiece from the first station to the second station after surface defects are at least partially removed from the first exposed surface and the portion of the side surface;

thereafter, directing the first exposed surface of the microfeature workpiece to engage the buffering pad at the second station to remove material from the first exposed surface before adding a new layer of material to the microfeature workpiece.

17. The apparatus of claim **16** wherein the surface defects include particulates resting on or at least partially embedded in the first exposed surface and/or the side surface.

18. The apparatus of claim **17** wherein engaging the first exposed surface includes removing the particulates from the first exposed surface and the side surface.

19. The apparatus of claim **16** wherein the buffering medium includes a buffering pad having a Shore D hardness of about zero. 35
